DESIGN FOR A TOOTH BRUSH

Elmer E. Hachman, Baltimore, Md.

Application March 27, 1936, Serial No. 61,812

Term of patent 14 years

To all whom it may concern:

Be it known that Elmer E. Hachman, a citizen of the United States, residing at Baltimore city, in the State of Maryland, has invented a certain new, original, and ornamental Design for a Tooth Brush, of which the following is a specification.

Reference is made to the accompanying drawing in which:

Fig. 1 is a longitudinal view of a brush showing the handle in perspective, and the fronts of the brush-heads facing the observer;

Fig. 2 is a longitudinal view of the brush showing the front side only of the handle, and the brush-heads in front perspective;

Fig. 3 is a longitudinal view of the brush showing an edge of the handle, and the brush-heads in rear perspective; and

Fig. 4 is an end view of the brush as seen from the right when the front of the handle is turned to a lateral inclination with respect to Fig. 3.

I claim:

The ornamental design for a tooth brush, as shown and described.

ELMER E. HACHMAN.
